Specification for Design.

Patented May 25, 1920.

Application filed March 11, 1920. Serial No. 365,077. Term of patent 14 years.

To all whom it may concern:

Be it known that I, JAMES A. O'NEIL, a citizen of the United States, residing at Lynn, in the county of Essex, State of Massachusetts, have invented a new, original, and ornamental Design for a Canopy for a Lamp-Globe, of which the following is a specification, reference being had to the accompanying drawing, forming a part thereof.

The accompanying drawing is a perspective view of my ornamental canopy for a lamp globe, which canopy is made of a light transmitting material.

What I claim is,—

The ornamental design for a canopy for a lamp globe as shown and described.

In witness whereof I have hereunto set my hand this eighth day of March, 1920.

JAMES A. O'NEIL.
